DESIGN FOR A BABY BED

Frances Perdue Davis, Atlanta, Ga.

Application April 19, 1947, Serial No. 138,507

Term of patent 14 years

(Cl. D5—5)

To all whom it may concern:

Be it known that I, Frances Perdue Davis, a citizen of the United States, residing at Atlanta, in the county of Fulton and State of Georgia, have invented a new, original, and ornamental Design for Baby Bed, of which the following is a specification, reference being had to the accompanying drawing, forming part thereof.

The figure is a perspective view of a baby bed, showing my new design.

The opposite side and back are the same as those disclosed.

I claim:

The ornamental design for a baby bed, as shown and described.

FRANCES PERDUE DAVIS.
